UNITED STATES PATENT OFFICE.

ISAAC T. DYER, OF CHICAGO, ILLINOIS, ASSIGNOR OF ONE-HALF TO ALEXANDER J. McDONALD, OF SAME PLACE.

MEANS FOR GENERATING POWER AND REUTILIZING THE EXHAUST OF LOCOMOTIVES AND ENGINES.

SPECIFICATION forming part of Letters Patent No. 431,225, dated July 1, 1890.

Application filed December 31, 1888. Renewed May 10, 1890. Serial No. 351,259. (No model.)

To all whom it may concern:

Be it known that I, ISAAC T. DYER, of Chicago, Cook county, Illinois, have invented certain new and useful Improvements in 5 Means for Generating Motive Pressure for and Reutilizing the Exhaust of Locomotives and Engines, of which the following is a full, clear, and exact description, reference being had to the accompanying drawings, and to the 10 letters of reference marked thereon.

Heretofore railroad locomotives and engines have been driven by steam almost exclusively, for although lately considerable experimenting has been done with gas and electricity, yet neither of the latter have been adopted.

The object of my invention is to provide such improvements to the present steam locomotive and engines that compressed air 20 may be utilized to drive them. This I do in such a manner that should it be desired to operate by steam it could be done without interfering with my improvements, or they could be used together in such manner as to 25 materially reduce the consumption of fuel, and so as to reutilize the exhaust, substantially as hereinafter fully described, and as illustrated in the drawings, in which—

Figure 1 is a side elevation of a locomotive 30 having my improvements applied thereto. Fig. 2 is a longitudinal vertical section of the same. Fig. 3 is a transverse vertical section taken on the plane just back of the smoke-stack.

35 In the drawings, A represents the boiler, B the fire-box, and C the smoke-arch, of a locomotive constructed and arranged in the usual manner.

D represents a compressed-air chamber, 40 which extends, preferably, from the cab to the smoke-arch of the locomotive, and surrounds and covers the upper half of boiler from side to side, as shown. The whistle, sand-box, man-hole, and bell are placed upon 45 and are supported by the shell of this chamber D.

Secured, preferably, to each side of the forward end of the boiler is a pump E, operated and actuated as hereinafter fully described, 50 which takes the exhaust-air from the cylinder

ders and forces it into the chamber D together with such quantities of free air, as is necessary to create in said chamber a pressure of from fifty to sixty pounds to the square inch. Preferably from the rear end of this chamber 55 there is an outlet-pipe F, which leads downward therefrom into a coil of pipes G, placed in the fire-box above the fire-bed in such position as not to interfere with the supplying of fuel thereto, and from this coil there is a 60 pipe G', which leads and discharges into the boiler.

In order to obtain the necessary pressure in chamber D and the boiler, the pumps are operated at the round-house or station by 65 hand or other outside agency. The fire is then started and the air in the boiler heated to such a degree as to increase the expansibility or pressure twofold, after which the air is utilized to drive the machine in the same 70 manner as steam. Back-pressure into the coil G from the boiler is prevented by a suitable valve in pipe G'; but as the air is exhausted from the boiler it is replenished by the air which is heated in and discharged 75 from coil G. As the engine or locomotive moves, the pumps are worked, and it is the design to reutilize the exhaust-air from the cylinders by exhausting into pipes which lead to said pumps.

When much of a fire is used, it is advisable to prevent the possibility of burning of the flues and walls of the fire-box. This is easily accomplished by recourse to the well-known expedient of suspending a suitable receptacle filled with water above the fire-bed in the furnace.

As it is desirable to sometimes use the exhaust to create the necessary draft from the fire-box, I have conceived the idea of one 80 of the pumps pumping in only the cold free atmosphere and the other pump on the opposite side pumping the exhaust back into chamber D. This I can easily do by putting a three-way valve in the neck of the exhaust-nozzle under the smoke-stack, which valve is under the complete control of the engineer and can be operated by him so as to direct the exhaust to the pumps or up the smoke-stack. The pumps E are secured in 85 90 95 100

the position stated upon brackets projecting laterally from the boiler, and they are connected at their lower ends to the arms *b b*, projecting from the ends of the transverse rock-shaft *c*, which is suitably journaled in hangers depending from the boiler. This rock-shaft *c* is actuated through the medium of link *d* by an eccentric *e* on the axle *H* of the forward drive-wheel.

10 As it might not be desirable, in view of the accumulated pressure in chamber *D*, and for reasons hereinbefore alluded to, to operate both pumps at once, I have arranged it so that the engineer can stop one of them. This I do by putting a sleeve *g* on one end of the rock-shaft, which is loose on said shaft, and which has the arm *b* (which would otherwise be secured to the corresponding end of the rock-shaft) projecting from it. This sleeve 15 is preferably journaled in the adjacent bearing and has its inner end serrated, so as to form a counterpart for the clutch *H'*, which, by means of a suitable feather is permitted to move longitudinally, but which rocks with 20 said rock-shaft. The clutch has a circumferential groove in its body, into which the inwardly-turned extremities of the forks or bifurcations of the end of a bell-crank *h* enter, and the lateral arm of this bell-crank has 25 connected to its end a rod *k*, which runs back to the cab and can be manipulated by the engineer. The pump itself may consist of an ordinary cylinder with a piston having a piston-head with a valve in it, which on its downward stroke forces the air out from before it 30 into the chamber *D* and draws in the air back of it. I prefer, however, to use the pumps for which I applied for Letters Patent December 26, 1888, Serial No. 279,597. I simply 35 connect the connecting-rods *a a* to the upper walking-beam of the pump, as shown in the drawings.

The air-brakes and whistle can be operated by supplies of air under pressure from the 40 chamber *D* as well as by the present system.

Cold air could be used and the fire in the fire-box dispensed with by adopting some means to operate the pumps and maintain the pressure in the boiler whenever the locomotive is at a standstill.

It is apparent that the coil *G* could be dispensed with, and such heat as was imparted to the air in the boiler by the heated gases of combustion passing through the flues in transit from the fire-box to the smoke-arch 55 alone be depended upon. In this event the chamber *D* as a cold-air reservoir would be useless, because the air could be pumped direct into the boiler.

If it should be desired to use steam and air 60 together, this could be easily done and would result not only in an economy of fuel, but the volume of steam necessary would be greatly reduced. Should it be desired to utilize the air only in case of accident, or because of the 65 water or fuel supplies giving out, my invention would be a great auxiliary to the present use of steam.

The system of feeding compressed air and reutilizing the exhaust of engines in generating a motive power could be used in heating apparatus of buildings, whether hot air, steam, or water be used. I prefer it for the use set forth, however.

What I claim as new is—

1. The combination, in a locomotive, with the boiler and fire-box, of the pumps *E E*, rock-shaft *c*, links *d*, eccentrics *e*, and axle *H* of the forward drive-wheel, as and for the purpose set forth.

2. The combination, in a locomotive, with the boiler, fire-box, and compressed-air chamber, of the pumps *E*, rock-shaft *c*, sleeve *g*, having its inner end serrated, clutch *H'*, link *d*, and eccentric *e* on the axle *H* of the forward drive-wheel, as set forth.

ISAAC T. DYER.
